Primary Examiner — Derrick Holland*Assistant Examiner* — Janice Lim*(74) Attorney, Agent, or Firm* — Seed IP Law Group LLP(57) **CLAIM**

The ornamental design for a hanging inverted bottle, substantially as shown and described.

DESCRIPTION

FIG. 1 is a top isometric view of a hanging inverted bottle, showing my new design.

FIG. 2 is a bottom isometric view thereof.

FIG. 3 is a front elevational view thereof.

FIG. 4 is a back elevational view thereof.

FIG. 5 is a left elevational view thereof.

FIG. 6 is a right elevational view thereof.

FIG. 7 is a top plan view thereof; and,

FIG. 8 is a bottom plan view thereof.

Stippling and tangent lines shown in the drawings represent the three-dimensional contour of the design. The dot-dash broken lines immediately adjacent to the claimed areas in the views represent the boundaries of the design and form no part thereof. The broken lines in the figures illustrate the portions of the design that form no part of the claim. None of the broken lines form any part of the claimed design.
